UNITED STATES PATENT OFFICE

JOHN E. DENNIS, OF LONDON, ONTARIO, CANADA

METAL WINDOW

Application filed March 8, 1928. Serial No. 260,196.

The principal objects of the invention are to devise a simple, strong and durable form of window frame construction which will enable the placing and removing of the sash in a very simple manner.

The principal features of the invention consist in the novel construction of a box frame and the construction and arrangement of removable flanged strips thereon whereby 10 adjustable guiding recesses are formed to receive the flanges of the window sash.

In the drawings, Figure 1 is a broken sectional perspective view of a window constructed in accordance with this invention.

15 Figure 2 is an enlarged vertical sectional view of the window structure.

Figure 3 is a transverse sectional view taken through both upper and lower sashes.

In the construction herein shown, the box 20 frame 1 is formed of substantially rectangular cross section having a longitudinal rib 2 formed at the outward side. A flanged strip 3 is secured to the outer face of the frame and the flange 4 thereof is secured 25 to the edge 5 of the rib 2 so that the edge of the flange projects inwardly.

A plurality of lugs 6 are punched up from the inner side 7 of the frame adjacent to the rib 2 and are pointed away from the rib.

30 A flanged metal strip 8 of substantially U-shape is placed against the inner face of the box frame with the flanged edge 9 extending under the lugs 6. The other flanged edge 10 of the strip 8 is provided with a plurality of transverse slots 11 through which the fastening screws 12 extend.

The strip 8 is formed with doubled flanged edges 13 and 14 which extend parallel with the face of the box frame in alignment with 40 the flange 4 of the strip 3. The edge 13 is spaced from the longitudinal edge of the flange 4 a distance sufficient to receive in a snug sliding fit the flange 15 of the sash 16. The slot thus formed may be adjusted by 45 loosening the screws 12 and moving the strip 8 toward or from the flange 4. The lugs 6 are set at an angle so that they may be readily adjusted.

50 A Z-shaped strip 17 of a corresponding depth to the depth of the strip 8 is secured

to the inner face of the box frame by screws 18 extending through transverse slots 19 and the edge 20 of the strip 17 may be adjusted to regulate the width of the slot between it and the flange 14 of the strip 8 to form a 55 snug sliding fit for the flange 21 of the sash 22.

The window sashes are preferably formed of T bars, the webs 15' and 21' of which form a snug sliding contact with the flat, 60 inward faces of the strips 8 and 17 respectively.

The flanges 15 and 21 extending into the slotted structure described form an effective wind break which together with the surface contact of the webs 15' and 21' provide a substantially dust and air tight joint. It will also be noted that the flanges 15 and 21 are flared slightly outward to more effectively 65 secure an air tight joint. 70

The continuation 23 of the flange 21 at the bottom of the lower sash forms a bevelled seal with the bevelled surface 24 of the sill 25. 75

The bottom rail 26 of the top sash is formed with a bevelled groove 27 into which a bevelled flange 28 of the top rail 29 of the lower sash engages in an air and dust tight joint.

It will be readily understood that a construction such as described will enable the sash being placed in position and individually adjusted in a very simple and expeditious manner. Further, when it is desired to remove a sash for any reason it is merely necessary to remove the few holding screws from the strip 17 and slip the strips out of place to allow the lower sash to be removed and if it be desired to remove the upper sash the removal of the screws 12 allows of the removal of the strip 8, when the sash may be withdrawn from the frame. 80 85

It will also be seen that if by reason of wear the sash become loose in the frame, the strips 8 and 17 may be adjusted by simply loosening the holding screws and then adjusting the strips into closer contact with the sash. 90 95

The various parts are of simple and inexpensive construction and they are very easily assembled. 100

What I claim as my invention is:—

1. In a metal window, the combination with **T**-bar sash, of a closed box frame having a flange extending inwardly toward the upper sash to slidably engage the projecting flange thereof, a longitudinal flanged strip adjustably and removably secured to the inner face of the box frame and having a sash-engaging portion spaced from the inner wall of said frame and slidably engaging the web and flange of the upper sash and the flange of the lower sash, and a **Z**-shaped flange strip having one of its edge flanges adjustably and removably secured to the inner wall of the box frame and supporting the other edge flange in slidable yielding engagement with the sash frame.
2. In a metal window, a box frame having a longitudinal rib at the outward side of its inner wall, said inner wall having a plurality of vertically aligned angularly disposed lugs projecting therefrom adjacent said rib, a **U**-shaped strip having the edge portions flanged laterally and abutting the inner wall of said frame in flat surface contact with one of said flanged edges engaging said wall lugs, a **Z**-shaped strip having a laterally flanged edge portion abutting the inner wall of said frame in flat surface contact, the free laterally flanged edge of said **U** strip and the laterally flanged edge portion of said **Z** strip each having a plurality of vertically spaced horizontally extending slots formed therein for the reception of fastening screws, fastening screws extending through said slots into the inner wall of said box frame and securing said **U** and **Z**-shaped strips in horizontally adjusted position and **T**-bar sash having their flanges extending snugly between said rib and the adjacent adjustably secured strip and between the adjustably secured strips.
3. In a metal window, the combination with a **T** bar sash and a box frame having a flat wall closing its inner side and a fixed flange spaced inwardly from the inner side thereof to slidably engage the outer side of the upper sash in edge contact, of a double flanged longitudinal strip secured to the inner wall of said frame and laterally adjustable thereon and having its intermediate portion engaging the web of the upper sash in flat surface contact and formed with lateral flanges spaced parallelly from the inner wall of the frame and engaging in edge contact with the adjacent faces and the flanges of the upper and lower sash, and a longitudinal strip secured to the inner wall of the box frame and laterally adjustable thereon and having a flanged portion spaced from the inner wall of said frame to engage the web and flange of the lower sash.

JOHN E. DENNIS.
